J. B. & S. S. STEWARDSON.

VALVE.

APPLICATION FILED OCT. 25, 1916.

1,242,734.

Patented Oct. 9, 1917.

UNITED STATES PATENT OFFICE.

JAMES B. STEWARDSON AND SAMUEL S. STEWARDSON, OF NORTH RANDALL TOWNSHIP, THOMAS COUNTY, KANSAS.

VALVE.

1,242,734.

Specification of Letters Patent.

Patented Oct. 9, 1917.

Application filed October 25, 1916. Serial No. 127,609.

To all whom it may concern:

Be it known that we, **JAMES B. STEWARDSON** and **SAMUEL S. STEWARDSON**, citizens of the United States, residing in North Randall township, in the county of Thomas and State of Kansas, have invented certain new and useful Improvements in Valves, of which the following is a specification, reference being had to the accompanying drawings, which form a part hereof.

Our invention relates to an attachment for internal combustion engines and consists of a valve for regulating the supply of moisture and air to the charge mixture.

15 The principal object is to provide means for successfully regulating the combination and supply of moisture and air and the operation of such regulation by means under the immediate control of the driver.

20 We attain these objects by means of the mechanism hereinafter described and illustrated in the accompanying drawings in which the single figure is a longitudinal sectional view of our improved valve.

25 The several parts are designated by ordinals to which reference is made in the following description.

Our valve comprises casing 4, flange or plate 5 by means of which the valve is secured to inside of dash, inside-gland 6, cap-gland 7, attached by threaded connection to an extension of said inside-gland, stuffing boxes 8 and 9, needle-stem 10, needle 11, needle-seat 12, needle-seat-cutoff 13, crank-arm 14 secured to cutoff 13, rod 15 pivotally secured to said crank-arm and connecting with the spark control lever by means of which the cutoff 13 is operated.

40 A groove 18 surrounds gland 6 and ports
19 therefrom provide entrance for the water
into chamber 20; such water being supplied
from the water jacket or other source
through pipe 21. The water, the quantity
being regulated by needle 11, passes from
45 chamber 20 through opening 22 in seat 12 to
chamber 23 in cutoff 13, where it mixes with
the air entering said chamber through open-
ing 24 provided therefor. A port 25 lead-
ing from the chamber 23 when the cutoff
50 13 is in open position meets port 26 through
the casing where the same connects with

pipe 27. This mixture of water and air

through port 25 passes into pipe 27 by means of which it is conducted to a tube or other means of supplying the moisture or air or both combined to the intake manifold through said ports 25 and 26. The cutoff 13 regulates the quantity of water and air passing through pipe 27 even cutting off the supply altogether when the ports are entirely separated from each other; thus assuring to the operator complete control of the supply of moisture and air to the intake manifold, thereby adapting such supply at all times to prevailing atmospheric conditions and providing a more uniform and effective explosive agent. Should there appear to be too much or too little water supplied to the charge mixture within the manifold such supply is regulated primarily by means of the needle-valve and when this is properly adjusted the operator may readily control the same by means of the spark control lever and cutoff as heretofore described.

Having thus described our invention what we claim as new and desire to secure by Letters Patent is—

In combination with an internal combustion engine, a regulating valve comprising a casing, inside-gland, needle-stem passing through a chamber in the interior of said gland and in threaded adjustment connection with said gland, a stuffing-box at the inner end of said inside-gland, a cap-gland to said inside-gland, a needle extension of said stem in relation to a seat provided with a port therethrough, a groove between the walls of the inside-gland and the casing, port connection between said chamber and said groove and port connection from said groove through the wall of said casing, a needle-seat cutoff in threaded adjustment connection with said casing, a chamber in the interior of said cutoff, a port through the needle-seat opening into said chamber, and an outlet port from said chamber through the wall of said casing. 80 85 90 95

JAMES B. STEWARDSON.
